PHILIP D. PARSONS, OF PHILADELPHIA, PENNSYLVANIA, ASSIGNOR TO SCOTT PAPER COMPANY, A CORPORATION OF PENNSYLVANIA.

PAPER TOWEL FOR TOILET PURPOSES.

1,158,550.

Specification of Letters Patent. Patented Nov. 2, 1915.

Application filed March 27, 1915. Serial No. 17,411.

To all whom it may concern:

Be it known that I, PHILIP D. PARSONS, a citizen of the United States, and resident of Philadelphia, county of Philadelphia, and 5 State of Pennsylvania, have invented an Improvement in Paper Towels for Toilet Purposes, of which the following is a specification.

This invention relates to paper towels for 10 toilet purposes and has for an object to provide folded paper towels which, when assembled in package form, shall be compact and suitable for use within a serving cabinet in such manner that individual towels may 15 be successively withdrawn from the package as desired.

More particularly, the object is to provide 20 a package of paper towels, each of which is so folded and arranged as to provide a plurality of positive and effective folded parts or means to be engaged by a discharging blade operatively mounted upon the cabinet, whereby manipulation of the said blade causes one of said folded parts or means to 25 be readily engaged and pushed through the discharge opening of the cabinet where it may be grasped and the towel withdrawn without objectionably disturbing the remainder of the towels within the cabinet.

30 More specifically stated, the folded towel sheets may be considered as having a body part formed by folding the sheet in such a manner as to provide a multiple ply thickness, two opposite end portions of which are 35 folded over the body part in a direction toward each other and these folded end parts in turn being reversely folded upon themselves to form a tab at each end of the sheet and extending substantially the length 40 thereof, which multi-ply tabs provide closed end portions so arranged as to be adapted for engagement by the discharging blade.

With the above and other objects in view, the nature of which will be more fully understood from the description hereinafter, 45 the invention consists in the novel construction of paper towels as hereinafter more fully described and defined in the claims.

50 Referring to the drawings: Figure 1 represents a sectional elevation of a portion of the serving cabinet showing the adaptation of my improved paper towel thereto; Fig. 2 represents a side elevation of sheets folded in accordance with my invention and arranged in package form; Fig. 3 represents

a similar elevation of a package formed in accordance with a modification of my invention; Fig. 4 represents a perspective of a portion of one of the towel sheets.

1 designates a preferred type of cabinet 60 for use with the towels of my invention and has its lower part provided with a transverse slot 2 through which the towel tab or means to be engaged by the discharging blade 3 may be projected. The blade 3 may be of 65 any desired form but as here shown it is pivoted and arranged to be reciprocated by the lever 4. The cabinet may also have the shelf or shoulder 5 at the side opposite the blade for supporting the package of towels 70 at one side and, if desired, the opposite or blade side of the cabinet may be similarly provided with a support 6.

Referring more particularly to the folded sheet shown in Fig. 4, 7 designates the body 75 part of the sheet which is formed by folding the sheet in the middle to provide a two-ply body structure, which is subsequently folded in the special form now to be described. It is manifest that whether the sheet, *per se*, is 80 single ply or multi-ply is a matter or secondary consideration, though this is the preferred form. Considering the sheet without regard to whether it is single or multi-ply, it is first folded on lines 8 and 9 parallel to 85 two opposite side edges of the sheet and parallel to each other, thereby forming two tab parts extending toward each other and over the body part between the folds and each of which tabs is again folded as indicated at 10 and 11 respectively, along lines parallel to the folds 8 and 9 to provide tab parts 12 of suitable width at the respective sides of the body part 7 corresponding to the 90 position of the folded tab. It will further 95 be noted that the folds 10 and 11 are so made that the free end parts 13 of the tabs are positioned and held between the parts 12 and the body part of the sheet, thereby effectively concealing and protecting the 100 said free ends. This construction provides two tabs, one at each edge of the folded sheet, which are of multi-ply thickness and with closed edges 10 and 11, said tabs adapted for engagement by the discharging blade 105 of the cabinet, either tab part being in the path of movement of the blade according to the position of the sheets within the cabinet.

In Fig. 2 I have shown the preferred embodiment of this folded sheet wherein the 110

tab parts 12 are at opposite sides of the body part and directed toward each other, thereby providing a folded towel which is reversible by inverting the package in the cabinet, so 5 that either tab may become the one to be engaged by the discharging blade, according to requirements.

In Fig. 3 I have shown a modified form 10 wherein both tabs are folded to the same side of the body of the sheet, thus making the sheet reversible in a horizontal plane to bring either tab into the path of the discharging blade as desired.

Sheets folded in the manner above de- 15 scribed not only present a uniform compact appearance but will stack up with stability to form a package the center of gravity of which passes through the body part 7 preferably between the tab portions and main- 20 tains the proper operative relation between the elements of the package. While I have referred to the reversibility of the package in use, especially with regard to its position within the cabinet, yet I do not wish to re- 25 strict myself in any way to this particular feature although I consider it the preferred manner of assembling the folded sheets to constitute the package.

It will now be apparent that I have pro- 30 vided a folded sheet having tabs of multiple thickness parallel to the body portion and oppositely directed, each of which has an end formed by a folded part of the sheet, for the purpose of providing multi-ply tabs 35 having relatively strong edges, adapted to be engaged by the discharging blade. The action of this blade, as will be understood, is to push or move the tab toward the discharging slot to force the same therethrough so 40 that it comes into a position where it may be grasped and the entire sheet readily withdrawn.

Having now described my invention, what I claim as new and desire to protect by Let- 45 ters Patent is:—

1. A paper towel consisting of a sheet folded upon itself to form a multi-ply body part, said body part being again folded upon two parallel lines to form tab parts extend- 50 ing toward each other, said tab parts being

respectively folded upon themselves along lines parallel to the body folds to bring the respective ends of the tabs between a part of the tab and the body of the sheet, whereby two oppositely directed tabs of multiple 55 thickness and closed folded edges are provided and having their free ends concealed and protected.

2. A paper towel consisting of a sheet having a body part folded upon two parallel 60 lines to form tab parts extending parallel to the body part and toward each other, said tab parts being reversely folded upon themselves along parallel lines to position the respective free end parts of the tabs between 65 a part of the tab and the body part of the sheet and provide two oppositely directed tabs of multiple thickness having free end portions concealed and protected.

3. A paper towel consisting of a sheet 70 folded upon two parallel lines to form a middle body part of restricted width, the folded parts at opposite sides of the body part being positioned parallel to the body part and at opposite sides thereof, said fold- 75 ed tab parts being again respectively folded upon themselves on lines parallel to the first mentioned folds to position the respective free ends of the tabs between a part of the tab and the body part of the sheet whereby 80 a tab of multiple thickness is provided at each side of the body of the sheet, having its ends concealed and protected.

4. A paper towel consisting of a sheet folded to provide a middle body portion and 85 two tab portions at each side thereof, said tab portions oppositely directed and each consisting of a multi-ply portion directed toward the other and each of said multi-ply tabs having a free tab portion directed away 90 from the corresponding portion of the other tab, said tabs providing shielded free end portions and folded exposed edge portions.

In testimony of which invention, I here-
unto set my hand.

PHILIP D. PARSONS.
